UNITED STATES PATENT OFFICE.

WILLIAM A. FOSTER, OF CHESTER, ASSIGNOR OF ONE-HALF TO S. H. JENNINGS, OF DEEP RIVER, CONNECTICUT.

CARRIAGE-JACK.

SPECIFICATION forming part of Letters Patent No. 256,309, dated April 11, 1882.

Application filed March 13, 1882. (No model.)

To all whom it may concern:

Be it known that I, WM. A. FOSTER, of Chester, in the county of Middlesex and State of Connecticut, have invented a new Improvement in Carriage-Jacks; and I do hereby declare the following, when taken in connection with the accompanying drawings and the letters of reference marked thereon, to be a full, clear, and exact description of the same, and which said drawings constitute part of this specification, and represent, in—

Figure 1, a perspective view of the two parts detached; Fig. 2, a vertical sectional view illustrating the operation.

This invention relates to an improvement in devices for raising carriage-axles for the removal of the wheels—as for lubricating, &c.—commonly called “carriage-jacks,” the object being a simple and compact device which may be readily adjusted to different elevations and be automatically locked in the supporting position; and it consists in the construction of the jack, as hereinafter described, and more particularly recited in the claim.

25 A represents the body or post, the lower end of which is to rest upon the floor or ground, as the case may be, and from its upper end downward is a vertical slot, B, transversely across which are several bars, a, more or less 30 in number, equidistant, or nearly so, from each other.

C is the lever, fitted at one end, b, to take hold beneath the axle of the carriage, the other, d, in convenient shape for the application of the hand in using the jack. The upper edge of the lever is constructed with a notch, e, so as to freely pass onto either of the bars a. On its opposite side is a segment-shaped surface, f, of which the lower part of the notch e is the center. This segment terminates back from the end b, as at h, where it forms substantially a shoulder, and so that, this shoulder h resting upon a bar below, as seen in Fig. 2, the notch e may be passed onto the bar above, as seen in broken lines, same figure, and when brought into that position the notch engages the bar as a fulcrum, and so that, then turning the lever backward, the segment-

shaped surface f will ride over the bar below, as seen in Fig. 2, until the end of the segment 50 is reached, where a shoulder, i, is formed. Then the lever will drop upon that shoulder, as indicated in broken lines, Fig. 2, and thus prevent the lever turning upward as the weight comes upon the other end, the notch and bar 55 above resisting the tendency of the lever to turn upon the bar below as a fulcrum.

The end of the lever is introduced beneath the axle in the usual manner, and while the lever, say, is in the upward position, (indicated in broken lines,) then the turning down of the lever causes the lifting end of the lever to rise, as indicated in broken lines, and take with it the axle until it arrives at the locking-shoulder i. From this position it is released by raising 65 the handle end of the lever, which carries the notch up onto the upper bar until the shoulder below will escape from the bar with which it was engaged. Then the lifting end of the lever will fall and permit the axle to drop. 70

The lever may be constructed with several locking-shoulders, the drawings showing two only.

The lever is removed from the base by simply reversing the operation by which it was 75 inserted.

This construction makes the jack so compact that it may be readily taken in a carriage without inconvenience. It is so simple that its use is readily understood, cannot get out 80 of order, and is of the cheapest character.

I claim—

The herein-described carriage-jack, consisting of the base A, constructed with the vertical slot B and provided with bars a transversely across the said slot, combined with the lever C, one end fitted for a handle, the other as the lifting end, constructed with a notch, e, upon one side, the segment-shaped surface f and locking-shoulder i upon the opposite side, substantially as described. 90

WILLIAM A. FOSTER.
